ATTORNEY

UNITED STATES PATENT OFFICE

HARRY HENRY MCKEE, OF CHICAGO, ILLINOIS, ASSIGNOR, BY MESNE ASSIGNMENTS, TO INDUSTRIAL PATENTS CORPORATION, OF CHICAGO, ILLINOIS, A CORPORATION OF DELAWARE

SHIPPING CONTAINER

Application filed September 27, 1930. Serial No. 484,825.

My invention relates to shipping containers adapted for self-refrigeration and the shipment of perishable food products.

One object of my invention is to provide an inexpensive shipping container for the shipment of perishable food products, such as meat, which may be utilized in combination with anhydrous refrigerant or natural water ice.

Another object of my invention is to provide a container of the class described, which has sufficient strength and rigidity to be handled and stacked in shipment in the manner in which wooden boxes are ordinarily handled and stacked, yet be light in weight, avoiding unnecessary tare.

Referring now to the drawings:

Figure 1 shows a preferred type of wire-bound skeleton wooden crate.

Figure 2 represents the crate shown in Figure 1, in which has been inserted a fibre carton.

Figure 3 represents the crate of Figure 1 with the fibre container of Figure 2, into which has been inserted a waxed bag and corrugated inserts.

Figure 4 is a view of Figure 3 in cross section.

Figure 5 is a transverse section showing the drain spout.

In one embodiment of the invention there is contemplated a skeleton wire bound crate in which is inserted a solid fibre carton. The carton extends at its upper end above the top of the crate and is foldable inwardly of the carton and crate over goods which may be disposed within the container thus formed.

The crate is preferably provided with a lid, which may be a hinged lid 1^a, through the instrumentality of the wires 1^b used in making up the wire bound crate, and the ends 1^c of the wires may be hooked, twisted or in any other well known manner connected together, as is obvious, to fasten the lid in closed position, as will be readily understood from the disclosure, particularly such as shown in Figs. 1 and 2, wherein the lid is shown in open position.

If it is desired to use the container in

combination with an anhydrous refrigerant, or for any other purpose, for that matter, a waxed bag 3 may be inserted in the container within the aforesaid carton 2, within which the products may be placed along with a suitable quantity of anhydrous refrigerant such as solidified carbon dioxide. The sides of the waxed bag are extended upwardly beyond the upper edge of the crate, as in the case of the carton, and these extended sides of the waxed bag are inherently foldable along with the inherently foldable sides of the carton for disposition under the lid when the latter is in closed position. This waxed bag acts as a seal against escape of carbon dioxide gas, preventing a too rapid disintegration of the refrigerant. If desired, corrugated or other liners 4 and 5 may be placed within the waxed bag within the container, and upper and lower corrugated pads 8 and 7, respectively, may be disposed within the waxed bag of the container. The lower pad 7 is preferably disposed on the bottom of the waxed bag, while the upper pad 8 is preferably of a size so that the edges thereof rest upon the upper edges of the liners 4 and 5, as shown particularly in Fig. 4.

Where it is desired to use the container in combination with natural or artificial water ice, small drain spouts 9 may be provided, and these spouts may lead from the bottom of the waterproof waxed bag, draining off the water and thus preventing waterlogging of the fibre container.

It is understood that changes may be made in the manner of making and construction of the container without departing from the spirit of the invention, as defined in the claims which follow.

I claim:

1. A shipping container comprising a relatively rigid and strong skeleton crate that provides bottom and upright wall portions, a fibre carton fitted within the crate and providing bottom, upright wall or side, and foldable top portions and constructed so that the foldable portions of the upright wall or side portions extend above the top of the crate and so that said portions which ex-

tend above the top of the crate are inwardly foldable into horizontal position to complete a closed carton, a waxed bag fitted within the fibre carton and having upright wall or

5 side portions that extend above the top of the crate whereby the portions of the bag which extend above the top of the crate are inwardly foldable to horizontal position to complete a closed bag, wall liners disposed

10 within the waxed bag along the upright inner faces of the latter and provided for maintaining the upright wall portions of the waxed bag adjacent the inner upright faces of the fibre carton, horizontally extending

15 pads arranged at the bottom and top of the container, the bottom pad being located within the waxed bag and resting thereupon, the wall liners being disposed so that the lower edges thereof engage the edge portions of

20 the bottom pad, the top pad having its edge portions resting upon the upper edge portions of the aforesaid wall liners and located in a plane adjacent but slightly below the top of the upright walls of the crate, the

25 upwardly extending portions of the carton and of the bag being foldable over the upper pad, and a lid for the skeleton crate whereby when closed it causes the crate to encase the carton on the top as well as at

30 the bottom and about the vertical walls of the latter.

2. A shipping container as defined in and by the claim last preceding, which is constructed for receiving a refrigerating medium and which is provided with conduit means leading from the interior of the waxed bag through the carton to the exterior of the container.

Signed at Chicago, Illinois, this 23rd day
40 of September, A. D. 1930.

HARRY HENRY McKEE.
